UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

Application filed June 10, 1924. Serial No. 719,112.

One object of my invention is to construct an electric switch, which is especially adapted for regulating the amount of current passing to an electric heater, or other devices requiring different amounts of current.

A further object of the invention is to construct the mechanism so that a switch plate can be raised clear of a stop plate when the switch spindle is turned in one direction, and can be lowered clear of the stop plate when the spindle is turned in the opposite direction.

In the present instance, the switch is arranged to control three different degrees of heat and to cut off the current, but it will be understood that the number of terminals can be increased, or decreased, without departing from the spirit of the invention.

While the improved switch is particularly adapted for use in connection with an electric heater, it will be understood that it can be used wherever a switch of this type is desired.

In the accompanying drawings:

Fig. 1 is a sectional elevation of my improved switch on the line 1—1, Fig. 2;

Fig. 2 is a sectional plan view on the line 2—2, Fig. 1;

Fig. 3 is a sectional plan view on the line 3—3, Fig. 1;

Figs. 4, 5 and 6 are diagrammatic views illustrating different positions of the catch plate in respect to the stop plate; and

Fig. 7 is a perspective view illustrating parts of the switch detached.

Referring to the drawings, 1 is the base of the switch. Located in a recess 2 in the base is a stop plate 3, which is shaped as shown in Fig. 7, and secured to the base by screws 4. Depending from the center of the stop plate is a bearing 5 for the lower end of the spindle 6. Below the bearing is a slotted washer 7, which locks the spindle in position. The portion 8 of the spindle has screw threads thereon and rests upon the top of the bearing so that the spindle is held from moving longitudinally in the bearing, yet is free to turn therein.

The body portion 9 of the switch is mounted on the spindle so as to have a limited movement thereon, which is controlled by the spindle through the medium of a coiled spring 10. The body portion 9 has switch plates 11 and 12, which are arranged

to come in contact with the spring members 13 of the terminals 14. Between these switch plates is a non-conducting disk 15. Above the disk is a non-conducting washer 16 and below the disk is a non-conducting washer 17. Metallic plates 18 and 19, and rods 20 clamp the parts of the body together, as shown clearly in Fig. 1. The rods pass through non-conducting sleeves 21. The body portion may be modified without departing from the essential features of the invention. The arrangement of the switch plates and terminals may also be varied.

Projecting from the plate 18 is an arm 18^a. Depending from a collar 22, secured to the spindle, is an arm 22^a. The ends of the spring 10 extend on each side of the arms, as shown clearly in Fig. 2 so that, when the spindle is turned clockwise, the upper end of the spring is engaged by the arm 22^a to shift the body portion 9. When the spindle is turned counter-clockwise, the lower end of the spring is engaged by the arm 22^a, which rotates the body portion in a corresponding direction.

Carried by the collar 22 is an indicator disk 23, which has indicating marks thereon that can be exposed through a slot 24 in the cap 25, which encloses the working parts of the switch. Secured to the spindle 6, above the cap, is a handle 26 of any suitable construction. The handle is held to the spindle by a nut 27.

The switch hereinbefore described is known as a "snap switch". The spring is contracted to a certain extent and the body portion of the switch plate is released and the spring snaps the body portion from one position to another. In order to hold the body portion in position, the stop plate 3 is provided with notches 28. The projecting portions 29 between the notches are inclined on the same lead as the thread of the screw 8, as shown clearly in Figs. 5, 6 and 7.

Mounted on the threaded portion 8 of the spindle 6 is a catch plate 30, which has projections 31 that are shaped to enter the notches 28 in the stop plate 3. These projections 31 are beveled slightly, as shown, and pass above or below the portions 29 of the stop plate, depending upon the direction of movement of the spindle. The catch plate 30 is notched at 32. Depending from the bottom plate 19 of the body 9 are arms 33, which extend into the notches 32 of the

catch plate so that, while the catch plate is free to move vertically, it must turn with the body portion when it is released from the control of the stop plate.

- 5 Referring to Figs. 4, 5 and 6 it will be seen that when the catch plate 30 is in mid position, Fig. 4, it is locked from turning by the stop plate 3, as its projections 31 are in the notches 28 of said stop plate. When the 10 handle is turned clockwise, the spring is compressed and is moved a certain number of degrees to raise the catch plate clear of the stop plate, as in Fig. 5. This movement releases the body portion and the spring snaps 15 the body portion to the next position. The catch plate, however, does not move the full extent of the movement of the spindle and the spring is still under tension. While the 20 projections of the body portion are in position above the recesses in the stop plate, they do not engage both sides of the notches. On the release of the handle, the spindle is moved backwards until the end of the spring comes in contact with the post on the body 25 portion. This movement causes the screw to move the catch plate vertically into the notches so that its projections are held between the two walls of the notches in the stop plate. This movement can be repeated 30 to turn the switch from the "Off" position to the "Low" position, the "Medium" position, and the "High" position.

When the spindle is turned anti-clockwise, 35 as in Fig. 6, the catch plate is lowered by the action of the screw until it is clear of the stop plate and the spring will snap the body portion from one terminal to another, as hereinbefore described.

I claim:

- 40 1. The combination in an electric switch, of a base; a stop plate secured thereto; a spindle; switch plates carried thereby; contacts arranged to be engaged by the switch plates, said spindle having a screw thereon; and a catch plate arranged to engage the 45 stop plate, said catch plate having a thread meshing with the thread of the screw so that, when the spindle is turned in one direction, the catch plate is raised above the stop plate, and, when the spindle is turned in the 50 reverse direction, it is moved below the stop plate.
2. The combination in a switch, of a base; a notched stop plate thereon; a notched catch plate having portions arranged to extend into the notches of the stop plate; a spindle having switch plates thereon; terminals arranged to be engaged by the switch plates; and means, on the spindle, for raising the catch plate above the stop plate when the spindle is turned in one direction, and for lowering the catch plate below the stop plate when the spindle is turned in the reverse direction.
- 65 3. The combination of a base; a notched

stop plate thereon, said plate having inclined projecting portions; a spindle having a screw thread thereon; a catch plate having a thread meshing with the screw thread and arranged to be raised or lowered on the movement of the spindle; a body portion having a switch plate; and a spring connection between the body portion and the spindle, said catch plate being guided on the body portion so that it will turn therewith by the action of the spring when the catch plate is below or above the stop plate.

4. The combination in a rotary snap switch, of a base; a stop plate having notches therein secured to the base; a spindle; a body portion mounted on the spindle, but arranged to rotate independently thereof to a limited extent; a spring engaged by the spindle and by the body portion, said spindle having a screw thread thereon; a catch plate having a thread meshing with the thread of the screw, and having portions aligning with the notches of the stop plate so that, when the plate is in a central position, the switch is held by the stop plate, and, when the spindle is turned clockwise, or counter clockwise, the catch plate is raised or lowered, releasing the body; a switch plate on the body; and terminals so located as to be engaged by the switch plate.

5. The combination in an electric switch, of a fixed stop-plate having inclined projections; a catch-plate arranged to engage the stop-plate; a screw-threaded spindle for raising the catch-plate to a point above the stop-plate or lowering it to a point below said stop-plate; a body portion connected to the catch-plate, said body portion having contact plates; and a spring for snapping the body portion from one position to another so that, when the catch-plate is moved out of alignment with the stop-plate, the body portion will snap from one position to another and the catch-plate will be moved into engagement with the stop-plate.

6. The combination in an electric switch, of a fixed stop plate having projections; a spindle having a screw thread, the projections of the stop plate being on the same lead as the threads of the screws; a catch plate having projections and arranged to engage the projections of the stop plate, and also having a thread meshing with the threads of the screw; a body portion mounted loosely on the spindle and connected to the catch plate; and means for snapping the body portion from one position to another in either direction when the catch plate is moved above or below the stop plate by the screw, said catch plate traveling on the screw to re-engage the stop plate at a predetermined point.

7. The combination in an electric switch, of a stop plate having spaced inclined projections; a catch plate having projections

engaging the stop plate; a body portion connected to the stop plate; a spindle; a screw on the spindle arranged to raise and lower the catch plate; and a spring for snapping the 5 body portion from one position to another, the spindle and the spring having excess movement, which allows the spring to return the spindle and moves the projections of the catch plate into the spaces between 10 the inclined projections of the stop plate.

8. The combination in an electric switch, of a stop plate having notches; inclined projections between the notches; a spindle having a screw of the same lead as the inclined

projections; a catch plate mounted on the 15 screw and having projections arranged to enter the notches in the stop plate; a body portion connected to the catch plate; and a spring between the body portion and the spindle, which, when the spindle is turned, 20 moves a given distance to release the catch plate and to snap the body portion from one position to another, said spring having an excess movement, which retracts the spindle, when released, and causes the screw to move 25 the projections of the catch plate in between the walls of the notches of the stop plate.

MONROE GUETT.
